HARRY A. DAVIS, OF HOPEDALE, MASSACHUSETTS, ASSIGNOR TO DRAPER CORPORATION, OF HOPEDALE, MASSACHUSETTS, A CORPORATION OF MAINE.

FILLING-END CLEARER.

Application filed May 21, 1927. Serial No. 193,180.

This invention relates to filling replenishing looms and more particularly to a filling end clearer for controlling the filling end leading from the ejected filling carrier that it may not be drawn into the shed during weaving.

It is now the common practice to provide filling replenishing looms with some character of controlling means for preventing the filling end leading from the ejected filling carrier to the shuttle from being drawn into the shed, and in some cases the filling end between the ejected filling carrier and shuttle has been clamped, so that as the lay 15 went back after replenishment, the filling end would be withdrawn from the shuttle. Such filling end controlling means, however, necessitates a number of parts at the replenishing side of the loom and complicates the 20 loom structure, and one of the objects of the present invention is to provide a filling end clearer of simple construction which will be effective in operation to secure the desired results.

In that type of filling end controller or clearer where a laterally extending arm is employed over which the ejected filling carrier passes during weaving, breakage of parts is liable to result should a filling carrier become trapped between the front of the laterally extending arm and the shuttle box as the lay goes back, and similarly should a filling carrier be trapped between the rear portion of the laterally extending 35 arm and the back of the shuttle box or chute leading therefrom, the laterally extending arm is liable to be broken or injured.

An important feature of the present invention therefore consists of a filling end 40 clearer wherein the laterally extending arm or thread engaging member is yieldingly mounted on its support for movement horizontally or substantially so, both in a frontward and backward direction, so that in case a filling carrier becomes trapped as above suggested, the laterally extending arm may yield on its pivotal support without breakage.

In this type of filling end clearer, also, it 45 frequently happens that the filling ends accumulate upon the laterally extending arm, even after they have been withdrawn from the shuttle, and owing to the recurring beat-up movements of the lay, they are liable to 55 be caught in the shuttle box and drawn into

the shed, with the result that imperfect cloth is produced. Another important feature of the present invention therefore consists of a filling end clearer wherein the laterally extending arm is downwardly inclined, so that filling ends may travel down the inclined laterally extending arm and drop out of the danger zone without special attention on the part of the loom attendant.

The invention and new features thereof and novel combination of parts will best be made clear from the following description and the accompanying drawings of one good form thereof.

In the drawings:

Fig. 1 is a perspective view of portions of a loom at the replenishing side, provided with the present invention;

Fig. 2 is a sectional elevation through the shuttle and shuttle box, showing the relation of parts on replenishment of filling;

Fig. 3 is a detached detail of the filling end clearer, its support being shown in section;

Fig. 4 is a section on the line 4—4 of Fig. 3; and

Fig. 5 is a sectional plan view showing by full and dotted lines the yielding action of the laterally and downwardly extending arm of the filling end clearer.

The loom frame 1 may be of usual construction and in the present instance has mounted thereon the hopper stand 2 which supports the rotary hopper 3 in which filling carriers 4 are mounted for movement to 90 transferring position, as usual.

Extending from the hopper stand 2 is the stud or dead shaft 5 on which is mounted the transfer 6 having the downwardly extending arm 7 to which is pivotally connected the dog 8 adapted to be engaged by a bunter 9 carried by the lay to effect replenishment of filling. The dog 8 is under the control of a train of mechanism for indicating when replenishment should be effected, but since the details of such mechanism form no part of the present invention, further description thereof is unnecessary.

Secured to the stud or dead shaft 5 is the 105 downwardly extending arm 10 which forms a support for the filling end clearer. The lower portion of the arm 10 is provided with a slot 11 in which is adjustably mounted the pin or support 12 which may be clamped in its vertically adjusted position by means 110

- of the clamping nuts 13 threaded to the support 12. The support 12 carries the slide supporting arm 14 which may be secured to the support 12 by means of a set screw 15.
- 5 Extending laterally from the arm 14 is the bolt 16 which passes through a slot 17 at right angles to the slot 11, and formed in the bracket 18, constituting appropriate guideways for the slide 19.
- 10 The bracket 18 is provided with bearings 20 and 21, through the latter of which the slide 19 extends, and forward of the bearing 21 the slide is provided with a stop shoulder 22. Extending forwardly from
- 15 the slide 19 is a pin 23, and between the bearings 20 and 21 is a spring 23* normally urging the slide 19 rearwardly, in which position it is limited by the stop 22. The slide 19 extends rearwardly of the bracket 18 and
- 20 has pivotally mounted on its rearwardly extending portion the laterally and downwardly extending filling engaging arm.
- In the present instance of the invention, the rear portion of the slide 19 is bifurcated, as indicated at 24, and in the bifurcated end portion of the slide is a block 25 pivotally connected at 26 to the slide 19. The block 25 carries the laterally and downwardly extending filling engaging arm 27 which may be appropriately secured to the block 25 by the portion 28 which extends into a slot in the block and has a down-turned end, as indicated at 29. The block 25 affords a convenient and practical means for supporting the laterally and downwardly extending filling engaging arm 27, but this construction may be varied without departing from the true scope of the actual invention.
- 35 Extending forwardly from the pivotal support 26, the block 25 has a projection 30, to the front end portion of which, at 31, is secured one end of a spring 32, the other end of the spring being connected at 33 with the slide 19. In order to protect the parts 40 of the spring and block, as hereinbefore described, the forwardly extending portion 30 of the block is contained within the bifurcation or space 24 of the slide, and similarly, the spring 32 is therein contained.
- 45 From the construction thus far described it will be apparent that the laterally and downwardly extending filling engaging arm 27 is free for swinging movement, both in a forward and rearward direction under the controlling influence of the spring 32 which by forward stress normally maintains the filling engaging arm 27 in its filling engaging position, as indicated in Figs. 1 and 3.
- 50 In some cases it is desirable to provide the lower portion of the shuttle box adjacent the opening formed therein for the passage of the ejected filling carrier, with a series of teeth 35, whereby the filling end leading
- 55 from the shuttle eye may engage such teeth

upon ejection of the filling carrier, but these may not always be necessary although they are herein shown.

The lay 36 is provided with the usual shuttle box 37 having the opening 38 for the passage of the ejected filling carrier, and the teeth 35, when used, may be formed on a plate 39, and secured to the lower portion of the shuttle box forward of the passage through which the ejected filling carrier passes. The lay may be provided with a bobbin chute 40, as usual, for directing the filling carriers downwardly and forwardly.

From the construction described it will be apparent that the laterally and downwardly extending filling engaging arm 27 is normally held in its filling engaging position, as indicated in Fig. 1, by means of the spring 32, and yet such filling engaging arm 27 may yield horizontally either forwardly or rearwardly, as indicated by full and dotted lines in Fig. 5.

When filling replenishment is effected, an ejected filling carrier will normally pass forward of the laterally and downwardly extending filling engaging arm 27, and the filling end *a* leading from the ejected carrier to the shuttle, will be laid over the arm 27, as indicated in Fig. 1, so that on backward movement of the lay after replenishment, the arm 27 will act to withdraw the filling end from the shuttle and shuttle box.

Should a filling carrier fail to pass forward of the filling engaging arm 27 and be trapped between the lay and the rear portion of the filling engaging arm, the latter may yield forwardly, as indicated by dotted lines in Fig. 5, the spring 32 in such case acting yieldingly to permit such swinging movement of the filling engaging arm, and thereby prevent breakage of parts. On the other hand, should an ejected filling carrier be trapped between the front of the filling engaging arm 27 and the front wall of the shuttle box opening, as may happen at times, the filling engaging arm 27 under the action of the spring 32 may yield rearwardly as the lay goes back to thereby prevent breakage of parts and finally to release the trapped filling carrier as the lay recedes from its front position.

Should the filling ends *a* loop about the laterally and downwardly inclined filling engaging arm 27, they will gradually move towards the end of the downwardly extending arm 27 owing to the vibration of the loom during weaving, and finally drop from the end of said arm out of the moving parts of the loom or danger zone, and consequently not be carried into the shed. Such release of the looped filling ends from the downwardly and laterally extending filling engaging arm is automatic and due in a measure at least to the vibrations of the loom

during weaving, so that the loom attendant is not called upon to gather the loose filling ends and remove them from the loom.

What is claimed is:

5. 1. In a filling replenishing loom, the combination of the lay, a shuttle box having an opening for the discharge of a filling carrier, and a filling end clearer comprising, a slide mounted frontward of the lay, a laterally extending arm pivotally mounted on the slide and a spring for normally holding the pivoted arm in position to engage the filling between the ejected filling carrier and shuttle with freedom for swinging movement of the arm on its pivotal connection with the slide.

2. In a filling replenishing loom, the combination of the lay, a shuttle box having an opening for the discharge of a filling carrier, a slide mounted frontward of the lay, a laterally extending arm pivotally connected to the rear portion of the slide for permissive swinging movement relative thereto frontwardly and rearwardly, and a spring between the slide and laterally extending arm normally acting to hold the arm in position to engage the filling between the ejected carrier and shuttle and yieldable to permit rearward swinging movement of the arm should a filling carrier be trapped between it and the lay as the lay goes back.

3. In a filling replenishing loom, the combination of the lay, a shuttle box having an opening for the discharge of a filling carrier, a slide mounted frontward of the lay, a spring normally urging the slide rearwardly, a laterally extending arm pivotally connected to the rear portion of the slide for permissive swinging movement relative thereto frontwardly and rearwardly, and a spring between the slide and laterally extending arm normally acting to hold the arm in position to engage the filling between the ejected carrier and shuttle and yieldable to permit rearward swinging movement of the arm should a filling carrier be trapped between it and the lay as the lay goes back.

4. In a filling replenishing loom, the combination of the lay, a shuttle box having an opening for the discharge of a filling carrier, a guideway at the front of the loom, a slide mounted in said guideway for movement towards and from the front of the loom, an arm pivotally mounted on the slide and having a filling engaging portion extending laterally for forward and rearward swinging movement in case an ejected filling carrier becomes trapped either in front or in rear of the arm, and a spring normally acting to hold the laterally extending portion of the arm in position to engage the filling between the ejected carrier and shuttle.

5. In a filling replenishing loom, the combination of the lay, a shuttle box having an opening for the discharge of a filling carrier, and a filling end clearer comprising a slide mounted for movement towards and from the front of the loom, an arm pivotally mounted on said slide and having a laterally and downwardly extending portion to engage the filling between an ejected carrier and the shuttle that filling looped over said laterally and downwardly extending portion of the arm may slide therefrom during the loom operation. 75

6. In a filling replenishing loom, the combination of the lay, a shuttle box having an opening for the discharge of a filling carrier, and a filling end clearer comprising a slide mounted for movement towards and from the front of the loom, an arm pivotally mounted on said slide and having a laterally and downwardly extending portion to engage the filling between an ejected carrier and the shuttle that filling looped over said laterally and downwardly extending portion of the arm may slide therefrom during the loom operation, and a spring normally acting to hold said arm with the filling engaging portion extending laterally and downwardly. 85

7. In a filling replenishing loom, the combination of the lay, a shuttle box having an opening for the discharge of a filling carrier, a guideway at the front of the loom, a slide mounted in said guideway for movement towards and from the front of the loom, a filling engaging arm pivotally mounted on said slide and extending laterally and downwardly therefrom, and a spring acting frontwardly between the arm and slide to normally hold the arm in its laterally and downwardly inclined position with freedom of swinging movement should an ejected filling carrier become trapped between the front of the arm and shuttle box as the lay goes back. 100 105

8. In a filling replenishing loom, the combination of the lay, a shuttle box having an opening for the discharge of a filling carrier, a guideway at the front of the loom, a slide mounted in said guideway for movement towards and from the front of the loom, a block pivotally mounted on the slide and having a part extending frontwardly from the pivotal mounting, a filling engaging arm carried by said block and extending laterally therefrom to engage the filling between the ejected carrier and shuttle, and a spring connected to said part of the block and to the slide and normally acting to hold the arm in position to engage the filling. 110 115 120

In testimony whereof, I have signed my name to this specification.

HARRY A. DAVIS.
